CLAIM

The ornamental design for a centrifugal pump, as shown and described.

DESCRIPTION

FIG. 1 is a lower rear perspective view of a centrifugal pump showing my new design in accordance with a first embodiment of the invention;

FIG. 2 is an upper front perspective view thereof;

FIG. 3 is a front elevation view thereof;

FIG. 4 is a rear elevation view thereof;

FIG. 5 is a left side view thereof;

FIG. 6 is a right side view thereof;

FIG. 7 is a top view thereof; and,

FIG. 8 is a bottom view thereof.
